UNITED STATES PATENT OFFICE

VERNON M. GREGG, OF CEDAR FALLS, IOWA

DENTIST'S BITE-TRAY

Application filed October 17, 1930. Serial No. 489,374.

My invention relates to improvements in bite trays, and the object of my improvement is to supply a convenient device of this character for dentists' use, having coacting parts with operating means therefor, permitting adjustments in use, and the making of impressions which secure casts for correct articulation in crown and bridge-work.

This object I have accomplished by the means which are hereinafter described and claimed, and which are illustrated in the accompanying drawings, in which Fig. 1 is an elevation of the inner face of the outer compression plate and its associated operating elements. Fig. 2 is an elevation of the outer face of said device. Fig. 3 is a horizontal medial section of my complete device including the coacting plate and string or thread, with a part of the split operating stem broken away. Fig. 4 is a vertical section of the elements shown in said Fig. 3 taken along the length of one reach of the thread, and Fig. 5 is a detail view of the headed split operating stem as removed from its tubular casing.

The coacting plates 1 and 2 are of elliptical configuration and are concaved or curvilinearly troughed lengthwise and forwardly, and also curved approximately in parallel rearwardly, the plate 2 being somewhat smaller than the plate 1. A hollow casing tube 3 is mounted and fastened in the forward longitudinal hollow of the front plate 1 medially at one end, and to project from the other end of said plate for a distance adapting it for manual use. A longitudinally split stem or shaft 9 has a discoidal head 8, preferably knurled, and the separated elastic parts of the stem 9 when sprung together, may be inserted and to loosely fit the interior walls of said tube 3, but leaving the split between said members open a desired space apart.

The forward part of the tube 3 medially over the plate 1 has a slot 4 lengthwise, and said plate and the opposite wall of the tube have registering holes 5 which are opposite end parts of said slot 4. In one rotational position of the split stem 9 its split is in communication with said slot and said holes as shown in Figs. 2 and 3, also Fig. 4.

The inner and smaller plate 2 is substan-

tially concentric with the outer plate 1, similarly shaped, whereby the plates may conform in general curvature to any portion of the toothed jaws of the wearer, wherever crown or bridge work is to be done, the plates being positioned without and within said portion respectively, after their interspace is filled with dental wax for receiving on upper and lower faces thereof bite impressions. Before filling the interspace of the plates, however, a waxed thread 7 medially looped as shown in Fig. 3, is passed through a pair of apertures 6 in said plate 2, said apertures being directly opposite the apertures 5 in plate 1, then the thread members are passed through the apertures 5 and those in the tubular casing 3 including the split of the shaft or stem 9 and the elongated slot 4 to project a sufficient distance therefrom. The wax is then inserted between the plates, the patient caused to take a bite of the interpolated wax with both jaws, and the operator turns the knurled head 8 of the split stem 9, causing the thread to wind thereon, tensioning it while drawing the plates together enough to compress the wax upon that portion of the jaws to which the device is applied. This produces a bite impression in the upper and lower parts of the wax where the teeth are naturally articulated. When the patient withdraws his or her teeth from the wax filling, the device may be removed from the mouth by use of the tube 3 as a handle. After a cast has been made in the usual way, from the impressions as positioned with the natural relation, the crown or other work may be done with certainty that the articulation is correct.

The different curvatures of the plates or trays permits them to fit anywhere about the opposed jaws. The thread loop may be severed, the split-shaft turned to release the thread, so that both plates may be released.

Having described my invention, what I claim as new and desire to secure by Letters Patent, is:

1. In combination, a pair of plates, and releasable thread connections therebetween, and a roller mounted on one plate operable when releasably connected to said connec-

tions to cause the plates to approach each other to hold a plastic filling to receive bite impressions from both jaws of a person.

2. In combination, a pair of curvate plates, substantially concentric to fit any portions of the opposed jaws of a wearer, and a looped thread connection removably engaged with one plate and also engaged with the other plate removably, and a split-roller mounted on the latter plate adapted to receive and wind up said connection to draw the plates together adjustably.

3. In combination, a pair of curvate plates, shaped in their vertical and longitudinal parts to fit upon portions of the opposed jaws of a wearer loosely when their interspace is filled with a plastic mass and a bite taken in said mass by both jaws of the wearer, a bearing mounted on the outer plate having a longitudinal bore and a longitudinal slot opening into the bore, both said plates having pairs of transversely alined holes opposite parts of said slot, a split shaft rotatable in the bearing bore with its split in one position in communication with said slot and said plate apertures, and a severable flexible cord looped medially to have its members passed through said apertures, split and slot, whereby when the shaft is rotated in one direction, the cord members are wound upon the shaft to draw together the plates adjustingly.

In testimony whereof I affix my signature.
VERNON M. GREGG.
